UNITED STATES PATENT OFFICE.

WILLIAM MULLEN, OF CHICAGO, ILLINOIS.

HOD.

SPECIFICATION forming part of Letters Patent No. 550,996, dated December 10, 1895.

Application filed February 6, 1895. Serial No. 537,495. (No model.)

To all whom it may concern:

Be it known that I, WILLIAM MULLEN, a citizen of the United States, residing at Chicago, in the county of Cook and State of Illinois, have invented a certain new and useful Improvement in Hods, (Case No. 1,) of which the following is a full, clear, concise, and exact description; reference being had to the accompanying drawings, forming a part of this specification.

My invention relates to hods for carrying mortar. Speaking generally, its object is to provide a construction which shall be strong, cheap, and durable.

The main side pieces of my hod are secured to a heavy central supporting piece or rail, the end of which projects forward to form the bumper. A metal rod passes under the nose-piece of the bumper rearwardly in grooves formed in the upper edges of the side pieces and at the rear through holes bored out therein in continuation of the grooves. The ends of these rods are provided with screws, and an iron brace secured to the back of the hod is placed over these projecting ends and secured in place by nuts. In the upper edge of the back of the hod I provide a groove. A clamp, preferably in the form of a rod, passes under the rail and upwardly along the sides and into the said groove in the upper edge of the back. The ends of this rod are provided with a suitable clamping device, preferably right and left hand screws, upon which the corresponding double nut is adapted to be turned to secure the rod tightly in place. It will thus be seen that by tightening the nuts provided upon the rearwardly-projecting ends of the rod passing from front to rear and also by tightening the double nut that all the parts of the hod are securely fastened together, and in case of shrinkage the parts may be brought together by further tightening of the nuts referred to.

A further feature of my invention consists in the manner of bracing the handle. The brace is preferably made of strap-iron, having a collar which is clamped about the handle a few inches below the rail and having three braces connected therewith—two at the side attached respectively to the side pieces of the hod and one brace secured under the rail, preferably about midway between the handle and the

bumper. The end of the brace under the rail is preferably secured in place by a bolt, the nut of the bolt holding the brace securely in place. The side pieces are preferably secured each by an ordinary wood-screw. The rail should be of hard wood—like oak, for example. Its sides are cut out to conform to the lower edges of the side pieces. Thus the rail in cross-section when inverted is shaped something like a railroad-rail, the web or portion between the lower corners of the side pieces being, say, an inch and a quarter, and the lower portion, which corresponds in shape to the tread of a railroad-rail, being wide enough so that the edges thereof will be flush with the outer surfaces of the sloping side pieces. A hole is tapped out through the rail for receiving the end of the handle which is screwed therein. The back piece of the hod is inserted in grooves provided in the side pieces and in the rail and held in place as already stated.

My invention will be more readily understood by reference to the accompanying drawings, in which—

Figure 1 is a perspective view of a hod illustrative of my invention. Fig. 2 is a detail view showing the projecting nose or bumper and the manner of fastening the rod or wire under the same. Fig. 3 is a rear elevation. Fig. 4 is a front elevation. Fig. 5 is a view showing the under side of the front end of the bumper and the preferable manner of securing the clamping wire or rod thereto. Fig. 6 is a sectional view of one of the side pieces, illustrating the clamping-rod extending rearwardly with a groove and opening provided therein and clamped in position by the nut at the end of the rod.

Like parts are indicated by similar letters of reference throughout the different figures.

The side pieces *a b* are secured at the bottom to the rail *c*, this rail having its lower outer edges flush with the lower edges of said side pieces and being grooved or cutaway centrally on each side to conform to the angles of the side pieces, which are thus fitted to the rail. The rail extends from the front to the rear of the hod and projects beyond the side pieces to form a nose or bumper *d*. The back *e*, as is usual, consists of a kite-shaped piece, which is fitted in grooves provided in the side

pieces and in the rail. The handle *f* is screwed into a threaded opening provided in suitable position through the rail.

Two adjustable clamping devices are provided for holding the parts together and for tightening up the joints in case of shrinkage of the lumber. The main clamping device is composed of the rod or heavy wire *g*, which, as illustrated, passes under the nose *d*, as 10 illustrated at *h*, Fig. 5, and from thence extends over grooves provided in the rounded edges of the side pieces and back through openings to the rear, terminating in screws *i*. Over these projecting ends *i* is placed 15 the bar or brace *k*, which bar may be of heavy strap-iron and secured centrally, as shown, to the back or kite-shaped piece *e*. By means of the nuts, which are screwed upon the threaded ends *i*, the side pieces *a b* and the 20 back *e* are securely clamped together.

The rounded upper portion of the back is provided with a groove. The clamping-wire *l*, which is placed around the rear ends of the side pieces *a b* and under the rail *c*, is brought 25 upwardly, so that the ends thereof rest in said groove. These ends are provided with right and left hand threads, respectively, and by means of the nut *m*, resting in the notch preferably provided at the center of the upper 30 end of the back piece, the wire or rod *l*, forming the vertically-placed clamp, are brought together. In this manner the side pieces *a b* with the rail are clamped to the kite-shaped piece *e*, forming the back of the hod. Staples 35 are preferably driven into the sides *a b* over the wire *l* to aid in securing the same in place, as shown. The collar *n*, forming a part of the device for bracing the handle, is fitted, preferably, tightly upon the handle. The 40 central brace *o* is pivoted between the ends of the collar and secured, preferably, by a bolt and nut, as shown, to the under side of the rail. The side braces *p p* are secured each by a screw, as shown, to the side pieces.

45 The rail, so to speak, forms the backbone of my hod, and it should, therefore, be of strong wood and of sufficient size to withstand the strain and shocks to which it is necessarily subjected.

50 Having thus described my invention, what I claim as new, and desire to secure by Letters Patent, is—

1. In a hod, the combination with a rail extending from front to rear, and adapted to 55 form a bumper, of the side pieces secured

thereto, the end piece secured between the side pieces, and the handle upon the end of which the rail is adapted to rest, whereby the weight of the load is transmitted to the handle through the rail which serves also as 60 a bumper; substantially as described.

2. In a hod, the combination with a rail extending from front to rear and adapted to form a bumper, said rail being cut away at the sides to form V shaped grooves, side pieces 65 secured to the rail, the squared edges thereof fitting in said grooves, the end piece secured between the side pieces, and the handle upon the end of which the rail is adapted to rest; whereby the downward thrust of the side 70 pieces is taken up by the rail and the load is transmitted to the handle through the rail which also serves as a bumper; substantially as described.

3. In a hod, the combination of the side 75 pieces *a b* and back piece *e*, with a rail *c*, binding rod *g* and strap *h*.

4. The combination in a hod, with the rail extending from front to rear and projecting to form a bumper, of the side pieces secured 80 thereto, a clamping rod extending from under the nose or bumper of the rail rearwardly over the side pieces, the kite-shaped back placed between the side pieces and fitted in 85 grooves provided therein and in the rail, and a brace or strap at the rear of said back with which the ends of the clamping rod are adjustably connected, substantially as described.

5. The combination in a hod, with the rail 90 extending from front to rear and projecting to form a bumper, of the side pieces secured thereto, a clamping rod extending from under the nose or bumper of the rail rearwardly over the side pieces, the kite-shaped back 95 placed between the side pieces and fitted in grooves provided therein and in the rail, a brace or strap at the rear of said back to which the ends of the clamping rod are adjustably connected, and a clamping rod surrounding the said back and passing over the side pieces and under the rail, said clamping rod being adapted to be loosened or tightened as required, substantially as described.

In witness whereof I hereunto subscribe 105 my name this 2d day of February, A. D. 1895.

WILLIAM MULLEN.
